FUEL INJECTION MECHANISM AND METHOD

Original Filed April 25, 1927 2 Sheets-Sheet 2

UNITED STATES PATENT OFFICE

CHARLES PAUL CLARK, OF CLEAN, AND CARL A. BJORNINSON, OF WELLSVILLE, NEW YORK, ASSIGNORS TO CLARK BROTHERS COMPANY, A CORPORATION OF NEW YORK

FUEL-INJECTION MECHANISM AND METHOD

Original application filed April 25, 1927, Serial No. 186,329. Patent No. 1,693,546, dated November 27, 1928. Divided and this application filed March 15, 1928. Serial No. 262,009.

This invention relates to an improvement in fuel injection mechanism and method, especially designed for an internal combustion engine, and is a division of our former application Serial No. 186,329, filed April 25, 5 1927, now Patent No. 1,693,546, November 27, 1928.

An object of the invention is to arrange the fuel inlet in alignment with and in the direction of the exhaust ports of the cylinder, so as to introduce the fuel at one side of the outer end of the cylinder and in the general direction of the exhaust port to insure of a thorough mixing of the fuel with the air used in scavenging the cylinder. Compressed air only is used in the scavenging operation, and near the completion thereof the fuel injection valve is opened directly in the cylinder to admit the fuel into the path of the air so as to have a thorough mixing thereof prior to the explosion.

In the usual type of two cycle gas engine, the charge (air and gas mixture) is precompressed to a few pounds above atmospheric pressure in a separate compression chamber. 25 The expanded gases exhaust through cylinder ports uncovered by the piston near the end of the expansion strokes. When their pressure has fallen nearly to atmospheric 30 pressure, the precompressed charge enters through ports also uncovered by the piston and sweeps out the burned charge. The process of exhausting the burned gases, scavenging of the cylinder and admitting the fresh 35 charge takes place through a period representing about one-fifth of the length of the expansion stroke and through an equal length at the first part of the compression stroke. During this process of scavenging, a large 40 percentage of the fresh charge is lost through the exhaust ports which are full open at the height of the scavenging period and remain open after this period is over, allowing a large percentage of the fresh charge to escape 45 into the exhaust line from the engine.

The space occupied by the gaseous fuel in the fresh charge is considerable and if compared with the cylinder volume, the ratio of this gas to air represents a proportionate 50 amount in loss of engine output.

If fresh air only was precompressed for the scavenging operation, the excess air will sweep the cylinder and enter the exhaust line, thereby insuring more complete scavenging, greater economy, and higher engine output. 55

In the accompanying drawings:—

Fig. 1 is a plan view of the complete fuel injection mechanism, as applied to an internal combustion engine;

Fig. 2 is a vertical section partly in side elevation of the same; and

Fig. 3 is a vertical section through the fuel injection valve.

As illustrated in Fig. 1, the fuel is drawn from any suitable source of supply, through 65 a pipe 1 to the pump and compressor 2, which is operated by means of a suitable motor 3, and the fuel is forced from the compressor 2 through a pipe 4 to a supply tank 5.

A reducing valve 6 is interposed in the 70 pipe 7 which extends from the supply tank 5 to the cylinder 8 for supplying the fuel thereto. This reducing valve 6 may be set to deliver the gaseous fuel at any suitable pressure desired, which will insure the most 75 economical operation of the engine.

The internal combustion engine to which this fuel injection mechanism may be applied may be of any suitable form and construction and is designated generally by the 80 numeral 9. The main drive shaft 10 of the engine 9 has the fly-wheels 11 fixed thereon, which are driven from the piston 12 operated in the cylinder 8. The manner of this drive is conventional and, being well understood, is not set forth in detail. 85

A lay shaft 13 is connected in any suitable manner with the drive shaft 10 to be rotated therefrom. The outer end of the lay shaft 90 13 is mounted in a bearing 14 supported by a suitable bracket 15 carried by the engine housing. This bracket is provided with a cover 16. The lay shaft 13 has a cam 17 fixed thereon, as clearly shown in Fig. 2, in 95 position to actuate a lever 19 pivoted to a bracket or arm carried by the supporting bracket 15. The outer end of the lever 19 supports a push rod 21, the upper end of which engages a horizontal lever 22 carried 100

by a shaft 23 mounted in bearings 24 in the cover 16.

The shaft 23 also carries a vertical arm 25 which is connected with a secondary push rod 26, as shown in Fig. 2. The outer end of the push rod 26 is operatively connected with one end of the valve lever 27 pivoted as at 28 in brackets 29 carried by a valve casing 30. As shown in Fig. 3, the opposite end of the lever 27 is connected with a valve stem 31 which carries a valve 32 in position to engage a valve seat 33 in the casing 30. The valve stem 31 has a disk 34 fixed thereon, and a spring 35 is interposed between this disk 34 and the casing 30. The interior of the casing communicates with the supply pipe 7 and receives a charge of fuel therefrom.

As shown in Fig. 2, a spark plug 36 is placed in the center of the end cover of the cylinder 8, and said spark plug is suitably connected with a magneto 37. The valve casing 30 is secured to the end of the cylinder 8 on one side of the spark plug 36. The gaseous fuel is discharged from the casing 30 about the valve 32 when unseated in a direction at an angle to the center axis of the cylinder 8, and in the general direction of the exhaust ports 38 arranged in one side of the cylinder in position to be covered and uncovered by the piston 12.

Arranged on the opposite side of the cylinder from the exhaust ports 38 is an air port 39, through which compressed air is supplied to the cylinder for the scavenging operation. This port is likewise adapted to be covered by the piston, and on the side next to the port 39 the piston 12 is provided with the shoulder 40 in position to direct the compressed air in an upward direction toward the fuel injection valve 32. It will be noted that the fuel injection valve is on the same side of the cylinder with the compressed air inlet port, although the fuel valve is in the end of the cylinder but at one side of said end, and the exhaust ports are arranged on the opposite side of the cylinder.

In the operation of the machine, the gas or fuel is pumped into the tank 5 by the compressor 2 from where it passes through the reducing valve 6 and the pipe 7 into the cylinder 8.

The rotation of the lay shaft 13 from the drive shaft 10 causes a rotation of the cam 17, which rocks the lever 19, causing a periodical longitudinal movement of the push rod 21 and by reason of the bell-crank levers 22 and 25 mounted on the shaft 23 causes a similar longitudinal movement of the push rod 26, which, in turn, rocks the lever 27 and periodically moves the valve stem 31 inward against the tension of the spring 35 to unseat the valve 32 for admitting a supply of fuel into the cylinder 8. The position of the injector valve 32 is most advantageous and,

as stated above, it is arranged at the opposite side of the cylinder from the exhaust ports 38 and in position to direct the discharge of fuel into the cylinder substantially in the direction of the exhaust ports. Fresh air only is used in the scavenging operation to force out the exhaust gases from the cylinder through the exhaust ports 38. This fresh air is precompressed and admitted to the cylinder through the port 39 during the back stroke of the piston and a portion of the return stroke, which uncovers this port, allowing the air to pass in and through the cylinder to force out the exhaust gases on the return stroke of the piston.

When the ports are partly closed, as shown in Fig. 2, the valve 32 is moved from its seat 33 to allow the injection of gaseous fuel into the cylinder. The shoulder 40 directs the air toward the injection valve 32 and during this forward motion this compressed air picks up the gaseous fuel which had just been admitted, resulting in an intimate mixture of gas and air. The motion of the mixture, when reaching the bottom of the cylinder, is deflected outward again, resulting in a revolving mass and insuring of complete mixture of the fuel and air. The fuel injection is completed when the working piston has traveled about forty-five per cent of the compression stroke, at which point the pressure in the cylinder and in the injection valve are about balanced.

In this manner, compressed air only is used for the scavenging operation and the fuel is admitted directly into the cylinder for mixture with the air at the close of the scavenging operation, which insures of a thorough mixing of air and gaseous fuel. The relation of the injection valve, the compressed air port 39, shoulder 40 and exhaust ports 38 insures of this thorough mixing operation.

We claim:

1. A method of introducing fuel into the cylinder of an internal combustion engine including introducing the fuel at one side of the outer end of the cylinder and in the general direction of the exhaust port thereof.

2. A method of introducing fuel into the cylinder of an internal combustion engine including the introduction of the fuel into one side of the outer end of the cylinder on substantially the opposite side from the exhaust port and directing said charge in the general direction of the exhaust port.

3. In a device of the character described, the combination of an internal combustion engine cylinder, having exhaust and scavenging ports therein the exhaust port being located on one side only thereof, and means located in the end of the cylinder on the opposite sides thereof for directing a charge of fuel in the general direction of the exhaust port.

4. In a device of the character described,

the combination of an internal combustion engine cylinder, having exhaust and scavenging ports in opposite sides only thereof, a piston operating in said cylinder for controlling said ports and means located in the end of the cylinder for directing a charge of fuel into the cylinder in the general direction of the exhaust port.

5. In a device of the character described, the combination of an internal combustion engine cylinder, having exhaust and scavenging ports in opposite sides only thereof, a piston operating in said cylinder for controlling said ports, and valve mechanism located 10 in the end of the cylinder at one side of the center thereof, and inclined relative to the center axis of the cylinder for directing a charge of fuel into the cylinder in the general direction of the exhaust port.

15 6. In an internal combustion engine, a cylinder having exhaust and scavenging ports in the sides thereof, a piston operatively mounted in said cylinder and controlling said exhaust and scavenging ports, and a valve 20 mechanism connected with the outer end of the cylinder and being disposed on the same side of the cylinder as the scavenging port, said valve mechanism directing a charge of fuel directly into the cylinder in the general 25 direction of the exhaust port.

30 7. In an internal combustion engine, a cylinder having exhaust and scavenging ports disposed approximately on opposite sides thereof, a piston operatively mounted in said cylinder, said piston having a shoulder 35 formed thereon on the side of the scavenging port and to direct the scavenging air toward the outer end of the cylinder, and valve mechanism connected with the outer end of the 40 cylinder and being disposed on the same side of the cylinder as the scavenging ports, said valve mechanism directing a charge of fuel directly into the cylinder at an angle to the axis of the cylinder and in the general 45 direction of the exhaust port.

50 8. In an internal combustion engine, a cylinder having one or more exhaust ports disposed on a side only thereof, and valve mechanism connected with the outer end of the cylinder and disposed on the opposite side 55 thereof from the exhaust port, said valve mechanism being arranged at an angle to the axis of the cylinder and directing a charge of fuel approximately in the direction of the exhaust port.

60 9. In an internal combustion engine, a cylinder having one or more exhaust ports disposed in one side only thereof, a scavenging port disposed on the opposite side of the cylinder from the exhaust port, fuel intake valve mechanism connected with the outer end of the cylinder and disposed on the opposite side thereof from the exhaust port, said valve mechanism having the axis thereof 65 extending at an acute angle to the axis of

the cylinder and approximately in the direction of the exhaust port to discharge a charge of fuel toward the exhaust port, and a piston operatively mounted in the cylinder and having means to direct scavenging air 70 toward the fuel intake valve mechanism.

In testimony whereof we affix our signatures.
